SIGNALING SYSTEM

Walter S. Lemmon, New York, N. Y., assignor to
 International Business Machines Corporation,
 New York, N. Y., a corporation of New York

Application June 16, 1934, Serial No. 730,906

2 Claims. (Cl. 178—88)

This invention relates to signaling systems, more particularly to printing telegraph systems and is suitably adaptable to both radio and wire network transmission.

5 The present invention will be explained in conjunction with a single impulse synchronous transmission system, in which the different characters to be transmitted and received are represented by single impulse signals which are definitely 10 located during particular timed intervals. Inasmuch as the wave shapes of the signals may be all the same length and amplitude with respect to time, they can be similarly dealt with in transmission.

15 This invention consists of a method and means for the transmission and reception of printing telegraph signals, the system being characterized by the transformation of the wave shape of the signal during the progress of its transmission and reception. It has been found in the development 20 of this system of transmission that a combination of functions is necessary in order to obtain the greatest reliability and maximum speed and efficiency over long distance radio circuits or wire networks.

25 As mentioned previously, broadly, the printing telegraph system embodied in this invention involves the shifting of the character impulse along the axis of a timed scale, the position of the impulse thereon determining the character to be selected. Therefore, it is important to have an impulse of extremely short duration sent out from the printing telegraph transmitter in order to insure accurate timing of the various impulses.

30 It has been found that this extremely short impulse is not particularly best suited for future transmission over the network involved to insure maximum efficiency of the system involved. This short impulse signal is then passed through a 35 tank circuit so that it is proportioned to a predetermined value fixed entirely by the constants of the tank circuit and one found to be most suitable for the transmission to be effected. Upon its reception from the radio or wire network trans-

40 mitter the impulse may have its crest distorted due to network characteristics of the line or characteristics of the radio circuit, such as reflections from the "Heaviside" layer. Usually, however, the front portion of the impulse wave is undistorted, so that by passing the received impulse through an abbreviator circuit, the particular section of the front portion of the wave may be selected and later used to actuate the selecting devices of the printing telegraph receiver, while 45 the rear portion of the wave, which is usually

distorted, is rejected by the abbreviator circuit. It is obvious that the "abbreviator" not only selects a predetermined portion of the wave of the received impulse but also reduces the length of the impulse which is of prime importance in allocating the impulse properly on the particular segment of the receiving distributor or commutator in the system. However, this short impulse is not practically suitable for operation of the character selecting devices, in order then to 10 obtain the maximum power transferred to the selecting devices of the printing receiver, the short impulse is again transformed to a predetermined size and shape most suitable for the particular selecting devices. 15

It has been found in this system, that a condenser, having a charging time constant matched to the duration of the pulse which then is discharged more slowly through a circuit with fixed constants, is suitable for the purpose. 20

It is therefore an object of the present invention to provide circuits for transforming the wave shape of the character signal in a particular manner, the particular characteristic shape of the impulse depending on its progression in the 25 transmission and reception cycle. It is obvious that this invention is not to be limited to the particular types of signal waves to be disclosed in conjunction with the description, since their purpose is solely for graphical illustration of the 30 theoretical progression of transformation of the wave shape during a transmission or reception cycle.

Various other objects and advantages of my invention will be obvious from the following particular description of one form of mechanism embodying the invention or from an inspection of the accompanying drawing and the invention also constitutes certain new and novel features of the construction and combination of parts hereinafter set forth and claimed. 35 40

In the drawing:

Fig. 1 shows schematically a system by means of which the invention may be carried out.

Figs. 2 to 8 inclusive are graphs illustrative of 45 the principle employed.

A clear understanding of the invention will be apparent by considering Fig. 1 in which A is a printing telegraph transmitter which may be of any well known type having a series of character pivoted key bars 10.

The telegraph transmitter should be so connected that when a character key is depressed an impulse of extremely short duration is generated. A preferred method of obtaining such 55

an impulse is fully described in U. S. Patent 1,927,077 issued to G. W. Watson so that the following brief description is sufficient. A separate contact 11 is associated with each individual key bar 10 and connected to contacts or segments 12 corresponding to the character represented by each key bar. Rotary arm 13 driven by any suitable means is adapted to engage the contacts 12 in rather rapid succession, this fact in addition 10 to the narrow construction of the transmitting commutator segments 12 cause the impulse to be of extremely short duration. Figure 2 represents a comparative graphic illustration of the pulse as it is produced by the discharge surge of 15 the condenser 14 coacting with the transmitting commutator 15. It is to be understood that an individual condenser 14 is associated with each character key bar 10, and is charged by depressing the key 10 to close the charging circuit 20 through contact 16 associated with the key bar 10, battery 17, condenser 14 and key bar 10. The condenser 14 is discharged during a predetermined interval of time when the rotary arm 13 engages the particular character contact or segment 12 through the circuit closed by contact 11 and fully described in the aforesaid patent.

The extremely short impulse as produced by the printer transmitter units and shown in Fig. 2 is then passed through a tank circuit C in Fig. 30 1 so that it is increased to a predetermined length. This circuit includes a capacitive reactance 18, inductive reactance 19 and non-inductive resistance 20 connected as shown and controls the transformation of the extremely short pulse 35 to a comparative longer pulse as shown in Figure 3.

This procedure helps to overcome slight mechanical inequalities in the transmitter distributing brush system, and it also enables the pulse to attain the proper length best suited for future transmission over the network involved. In radio circuits the lengthening out of the extremely short pulse in Fig. 2 before feeding it into the wave transmitter serves a useful purpose inasmuch as it then becomes most suitable for the keying circuits at present involved in vacuum tube transmitters in a manner well known to those acquainted in the art. The transformation effect of the circuit as represented at C is fixed entirely 50 by the selection of the L, C, and R constants of the said circuit.

From the tank circuit C, just described, the pulse is fed to the radio or line wave transmitter D, to effect modulation of the carrier frequency 55 by the particular signal frequency in a manner that is well known and need not be further explained. In Figure 4 the illustration shows the effect of the signal wave modulating the carrier wave. In Figure 5, the pulse is shown as received 60 at E, the usual type wave receiver unit, with its crest distorted due to the network characteristics of the line, or characteristics of the radio circuit, such as reflections from the "Heaviside" layer. 65 The front portion of the pulse, however, is usually undistorted as shown. In order to remedy the effects created by the distorted portion of the pulse it is necessary to "cut-off" that portion including the distortion. This is done with 70 what shall be termed an abbreviator circuit as indicated at F in Fig. 1. The grid of the thermionic tube 21, which is connected in accordance with standard practice for an amplifying stage, is biased at a high negative potential so as to prevent plate current from flowing in the tube

when the grid is not excited from some outside source.

If an appreciable amount of current were flowing through the tube this would prevent the charging of the condenser 22 to the full voltage of the B-supply. Through the resistor 23 the condenser 22 charges relatively slowly. When the grid of the tube 21 is energized and a positive voltage is impressed thereon, the condenser 22 discharges through the resistor 24, inductive reactance 25 and the tube 21. The length of time required for the said condenser to be discharged is determined by the constants of the circuit, namely, the capacitive reactance of condenser 22 and the impedance of the inductive reactance 25 15 and resistance 24, and the plate resistance of the tube 21. As soon as the condenser 22 is discharged the plate current in the said circuit is reduced to a negligible amount on account of the high resistance of the circuit due to the resistances 23 and 24. Thus no appreciable amount of current flows in the said circuit even though the grid of the tube remains positive for a considerable period after the condenser 22 has been discharged. Therefore by selecting the proper L, 20 C, and R constants impulses of very short duration may be obtained. In this manner not only are extremely short impulses obtained and necessary for extreme accuracy in printing telegraph systems, but the amplitude of the pulses are always a consistent value, which as mentioned above may be of any predetermined value depending on the constants selected.

Referring to Figure 6 an illustration of the pulse obtained from the circuit just described 35 is shown and which is abbreviated as compared to the pulse shown in the previous Fig. 5. It is to be noted that the distorted portions of the crest of the wave in Fig. 5 do not appear in the pulse from the abbreviator circuit. The output of the 40 said circuit is connected to an amplifier G, the effect of which is to increase the amplitude of the pulse as shown in Figure 7. The output of the amplifier is then connected to the receiving commutator or distributor H and the printing telegraph receiver J, in a manner fully disclosed in the aforesaid Watson patent. It is understood that the rotary arm 26 of the distributor H is rotated in synchronism with the rotating arm 13 of distributor B which is disclosed in the said patent. 50 It is well known how the synchronous distributors are used in the art and applied to this type of system to effect the correct selection of characters and needs no further explanation.

The abbreviated pulse from the circuit as 55 shown in F and the amplifier G is then conducted through the distributor H. Using such an extremely short pulse also has the advantage of permitting a considerable drift of the pulse back and forth across the corresponding distributor 60 segments or contacts 27 before it shifts off the segment, overlapping the adjacent segment and thereby causing an erroneous character to be printed. It is obvious with this allowable tolerance in allocating the impulses on the distributor segments 27, the rotary arms 13 and 26 need not be held in synchronism as accurately as when a longer pulse is used.

However, it has been found that the shortened impulse as shown in Figures 6 and 7 is not effective, due to its short duration to operate the solenoid 28 connected to the character key bar 29, due to the inductance of the solenoid coil. It is therefore necessary to transform the received pulse again so that the maximum power may be

transferred to the solenoid 28 regardless of the extreme brevity of the original actuating pulse. For this reason the condenser 30 is used and connected as shown in the diagram, and which is selected to have a charging time constant to match the duration of the pulse. The condenser 30 is first charged by the received impulse and then discharges through the shunt connected solenoid 28 at a slower rate determined by the 10 impedance characteristics of the said shunt circuit to effect printing of the selected character.

What is claimed is:

1. A system of the character described comprising, in combination, a transmitting station having means to transmit successive impulses, a receiving station having means to receive said impulses including a thermionic device having an input circuit including a grid element connected to be energized by the last mentioned impulses and an output circuit including an anode element, said output circuit operated each time the grid element is energized, a resistor and condenser connected in series included in the said output circuit, and means to charge the condenser during the intervals when the impulses are not impressed upon the grid element, said condenser adapted to be discharged through the output circuit each time the output circuit is operated by the impulses causing the output circuit to be energized for a timed interval less than

the period of energization of the input circuit, a recording device, and a circuit connecting the recording device in shunt to said resistor so as to operate the recording device each time the said output circuit is energized.

2. A system of the character described comprising, in combination, a transmitting station having means to transmit successive impulses, a receiving station having means to receive said impulses including a thermionic device having an output circuit including a grid element connected to be energized by the last mentioned impulses and an output circuit including an anode element, said output circuit operated each time the grid element is energized, a resistor and condenser connected in series included in said output circuit, and means including a resistor and an energy source independent of the signal source to charge the condenser during intervals the impulses are not impressed upon the grid element, said condenser adapted to be discharged through the output circuit each time the output circuit is operated by the impulses causing the output circuit to be energized for a timed interval less than the period of energization of the input circuit, and a work circuit connected across the first mentioned resistor energized each time the output circuit is energized.
